Edgar A. Jones,
By B. F. Chapman, Attorney.

UNITED STATES PATENT OFFICE.

EDGAR A. JONES, OF THREE RIVERS, MICHIGAN.

SPRING.

SPECIFICATION forming part of Letters Patent No. 326,039, dated September 8, 1885.

Application filed January 27, 1885. (No model.)

To all whom it may concern:

Be it known that I, EDGAR A. JONES, of Three Rivers, in the county of St. Joseph and State of Michigan, have invented certain new and useful Improvements in Springs; and I do hereby declare the following to be a full, clear, and exact description of the invention, such as will enable others skilled in the art to which it appertains to make and use the same.

10 My invention relates to an improvement in springs for bed-bottoms, the object of the same being to provide a device of this character by means of which a durable and efficient support will be afforded equably to all portions of a bed.

15 A further object is to provide a device of this character which shall be simple and economical in construction and durable and efficient in use; and with these ends in view my invention consists in a coil-spring adapted to connect with side and opposite spring, thus rendering an intermediate support between the slats and springs secured thereto.

20 My invention further consists in the certain details of construction and combinations of parts, as will be hereinafter described, and pointed out in the claim.

25 In the accompanying drawings, Figure 1 represents a plan view of a bed bottom composed of the improved springs. Fig. 2 is a view in side elevation of one of the springs secured to a slat. Fig. 3 shows an enlarged view of the hooked end of the lateral extension of the springs. Figs. 4 and 5 are views of modified forms of springs.

30 The springs *a* are made of ordinary bed-spring wire, and can be of any desired size and shape, and each is provided at its lower end with the spring-clamp *b*, by means of which it is securely held in position on the bed-slat. The spring-clamps are made integral with the spring proper, and each is formed by bending the lower coil downward a suitable distance and then inward, terminating in an upwardly-projecting end, *c*, which latter is situated approximately to the vertical axis of the spring. The space between the upwardly-projecting end of the clamp and the lower coil of the spring is slightly smaller than the slat, so that 35 it becomes necessary when securing the springs to the slats to increase the space, which is done by drawing the spring-clamp downward. The

upper coil, *d*, of the spring is extended laterally a sufficient distance and then turned backward, forming an acute angle or **V** shape. 55 The free end of the spring is provided with the hook *g*, formed at right angles to the horizontal axis of the spring.

The springs are attached to a bed in the following manner: One of the springs is first 60 secured to the head-slat *h* by means of the spring-clamp *b*. The next spring is then placed in position on the slat, the upper coil, *d*, thereof having been first slipped through the **V**-shape angle *e* in the laterally-adjacent spring, and 65 when secured the upper coil engages the angle, as shown at *i* in the drawings. After the upper row of springs have been placed in position, as described, the springs continue to be secured to the slats below, and the hooked ends *g* engage with the upper portions of the upper coils of the longitudinally-adjacent springs below, thus affording a secure attachment and a complete net-work of wire over the entire surface 70 of the bed.

75 The springs attached to the foot-slat *j* are provided with the lateral extension and hooked end only, thus dispensing with the **V**-shaped section, and the hooks are attached to the laterally-adjacent springs, as shown.

80 At one side of the bed the springs are reversed and placed on frame. The lower edge of the slat and the **V**-shaped angle of the arm engages with the upper coil of the laterally-adjacent spring in such a manner as to form 85 a double row of arms between the slats, thus leaving the outside row of springs firmly secured and smooth upon their outer edge.

85 Another modification of this device for connecting the top of the springs is shown in Fig. 4, in which the lateral extension of the top coil of the spring is bent over back at the acute or **V**-shaped angle, at a less distance from the coil, is then extended back laterally far enough to meet the elbow to the adjoining spring on the 90 same slat, and then bent or curved and brought back about or nearly half-way, the end terminating in the hook *g*, to attach to the upper coil of the longitudinally-adjacent spring. By this method the place of contact with the laterally-adjacent spring is at the point where the ends 95 of the arms meet, instead of directly on the upper coil of the spring.

100 A further slight modification is shown in

Fig. 5, in which the lateral extension of the top coil is cut off somewhat shorter, and the curve in the wire near the hook *g* omitted, as seen in the drawings.

It will be seen that the construction described overcomes the defect heretofore experienced in the use of spiral springs, as the space between the several springs is filled by the curved extensions, and the bed is thus supported at every point.

These springs can be manufactured at a small initial cost and applied to a bed without the use of skilled labor, and are therefore specially adapted to be made and sold by persons of ordinary capability and limited capital. They are simple in construction and durable and efficient in use.

I am aware that it is not broadly new to provide a bed-spring with a bent arm constructed to be passed through or around the top coil of a spring on the adjacent slat, and thence back to the adjacent spring on the same slat. In this device above referred to, and in others wherein a bent arm passes through the top coil of an adjacent spring, it is impossible to adjust the springs toward or away from each other without turning the spring on the slat or without cramping or bending the arms thereof. In my device the arm of one spring engages the bent arm of the adjacent spring on the same slat. This permits the arm of one spring to slide freely on the arm of the adjacent spring;

hence I am enabled to move the springs on the same slat closer together or farther apart without turning the springs on the slat and without straining or bending the springs or arms.

I am aware that it is also old to bend the free end of the upper coil of a spring to form a loop or hook; hence I make no claim to this part, separately considered; but,

Having fully described my invention, what I claim as new, and desire to secure by Letters Patent, is—

A bed-spring having a straight arm or extension forming a continuation of the upper coil thereof, the said straight arm being provided with a continuation extending rearwardly in a diagonal direction, the latter having a hook-shaped end, the said straight arm adapted to rest parallel or approximately parallel with the slat and in a line, and interlock with the straight arm of the next spring, whereby the springs can be moved toward and away from each other without straining the springs or arms, substantially as described.

In testimony whereof I have signed this specification in the presence of two subscribing witnesses.

EDGAR A. JONES.
